UNITED STATES PATENT OFFICE

ANDRÉ MAURICE GAY, OF WEST NEWTON, MASSACHUSETTS

DEVICE FOR EFFECTING PERMANENT WAVES IN HAIR

Application filed September 27, 1929. Serial No. 395,554.

This invention relates to devices for waving or curling hair and has for its object the production of a simple but effective tool of this character which may be used to advantage in the marcel waving of ladies hair.

This object is attained by the mechanism illustrated in the accompanying drawing.

For the purpose of illustrating the invention, one preferred form thereof is illustrated in the drawings, this form having been found to give satisfactory and reliable results, although it is to be understood that the various instrumentalities of which the invention consists can be variously arranged and organized, and the invention is not limited to the precise arrangement and organization of these instrumentalities as herein shown and described except as required by the scope of the appended claims.

20 Of the drawings

Figure 1 represents a plan of a device embodying the principles of the present invention.

Figure 2 represents a side elevation of 25 same.

Figure 3 represents a longitudinal section of same on line 3, 3, on Fig. 2.

Figure 4 represents a longitudinal section of same on line 4, 4, on Fig. 1, with the inner 30 rod removed.

Figure 5 represents an elevation of the inner locking member.

Figure 6 represents a section of a portion of the device on line 6, 6, on Fig. 3.

35 Figure 7 represents a transverse section of same on line 7, 7, on Fig. 6.

Figure 8 represents an elevation of the opposite end of the device.

40 Figure 9 represents a transverse section of the inner locking member on line 9, 9, on Fig. 5, and

Figure 10 represents a portion of the device showing how a lock of hair is wound thereon to obtain a permanent marcel wave.

45 Similar characters indicate like parts throughout the several figures of the drawings.

In the drawings, 10 is a tubular member in 50 which is disposed a rod 11 having a hook 12

at one end thereof, the opposite end 13 being threaded and having a nut 14 thereon.

This rod 11 has a key 15 extending therefrom into a slot 16 in the bore of the tubular member 10 so that when the rod 11 is adjusted 55 endwise it is prevented from rotating about its axis.

Brazed or welded to one end of the tubular member 10 is a member 17 having a recess 18 therein to receive the hook 12 when moved 60 to the right of Fig. 3 of the drawings.

This end movement of the rod 11 is effected by rotating the nut 14 on the threaded end 13 of said rod.

A lock of hair is inserted into the space 65 19 of the hook 12 when in the position shown in Fig. 3 of the drawing.

After this lock of hair has been thus inserted the rotation of the nut 14 upon the threaded end 13 of the rod 12 will cause the 70 lock to be jammed against the end 20 of the tubular member 10 and firmly held in position, this end 20 being of the necessary thickness to permit its entrance into the space 19.

The tubular member 10 is provided on its 75 outer surface with a plurality of projections 21 curved in one direction and also has another projection 22 which is curved in the opposite direction.

The lock of hair held by the hook 12 is 80 wound about the tubular member 10 and in the spaces 23 between the projections 21.

The end 24 of the tubular member adjacent the projection 22 is threaded as indicated in Fig. 4 and has mounted thereon a nut 25 having a hub 26 provided with an annular groove 85 27 into which extends a pin 28 in a nonrotatable member 29.

This nonrotatable member has a hub 30 with a slot 31 therein in which is positioned 90 the projection 22, said projection 22 preventing the rotation of the member 29.

When the projection 22 and the nonrotatable member 29 are in the relative positions shown in Fig. 6 of the drawings, the lock of 95 hair wound about the tubular member 10 may be inserted into the space 32 of the projection 22 and then by rotating the nut 25 the nonrotatable member 29 will be forced toward the hook 22, this nonrotatable member hav-

ing a recess 33 therein adapted to receive said projection 22.

When this has been accomplished the lock of hair held at one end by the locking hook 12 and wound about the tubular member 10 will be gripped at the opposite end of the tubular member 10 so that it will be retained in place until the desired wave or curl in the lock of hair has been attained.

10 The inner wall of the recess 18 in the member 17 has oppositely disposed depressions 34 therein to receive the lock of hair positioned in the space 19 and extending over the outer end of the hook 12.

15 The inner wall of the recess 33 also has oppositely disposed depressions 35 to receive the lock of hair in the space 32 of the projection 22 and extending over said projection.

20 This provides a ready means of securely holding a lock of hair wound about the tubular member 10 while forming a wave or curl therein.

25 In obtaining a permanent wave to ladies' hair, a plurality of these devices are used to hold the various locks of hair in position while heat is being applied to give permanency to the waves of hair caused by the various locks being wound about the tubular members 10.

30 The curved projections 22 provide a means for retaining the coils of each lock of hair wholly separated as it is wound about the tubular member 10, thus producing a better result than could otherwise be obtained.

35 By means of this device the lock of hair 36 may be gripped close to the scalp which is a great advantage, as then waves may be made for the entire length of the lock.

40 It is obvious that the device may be dismantled quickly and each part thoroughly cleaned in order to keep it in perfect sanitary condition.

45 The gripping of the lock of hair 36 by means of hook 12 obviates the use of strings and clamps now in quite general use.

By the use of the device there is a great saving in time and labor and the lock of hair will be firmly held without disturbing the texture of the hair.

50 By having the hair-gripping hook 12 enclosed in the pocket or recess 18, the hair is prevented from getting loose or tangled which would be very harmful to the hair.

55 The projections 21 extending laterally from the member 10 form a comb-like structure upon which the lock of hair 36 may be wound in a particular way in order to effect a permanent marcel wave therein.

60 By providing the hood 22 and the member 29 coacting therewith the lock of hair 36 may be gripped near its outer end thus dispensing with the use of strings and saving much time and labor.

65 In Fig. 10 is shown the manner of winding

the lock of hair 36 around the member 10 and the various projections 21.

It will be noted that this lock of hair 36 passes around alternate projections 21 on one side of said projections and on the opposite sides of the intermediate projections.

When wound in this manner and held taut at opposite ends during the heating operation, a marcel wave will be imparted to the lock of hair which will last for a very long time.

It is believed that the operation and many advantages of the invention will be understood without further description.

Having thus described my invention, I claim—

1. A device of the character described comprising a tubular member provided with a plurality of projections curved in one direction and a single projection curved in the opposite direction; a rod enclosed in and adjustable endwise of said member having a hair-gripping hook at one end; and hair-gripping means at the opposite end of said tubular member coacting with said single projection.

2. A device of the character described comprising a tubular member provided with a plurality of projections curved in one direction and a single projection curved in the opposite direction; a rod enclosed in and adjustable endwise of said member having a hair-gripping hook at one end, said rod having a key movable in a slot extending longitudinally of said tubular member; and hair-gripping means at the opposite end of said tubular member coacting with said single projection.

3. A device of the character described comprising a tubular member provided with a plurality of projections curved in one direction and a single projection curved in the opposite direction; a rod enclosed in and adjustable endwise of said member having a hair-gripping hook at one end; a recess on one end of said tubular member to receive said hook when moved endwise; and hair-gripping means at the opposite end of said tubular member coacting with said single projection.

4. A device of the character described comprising a tubular member provided with a plurality of projections curved in one direction and a single projection curved in the opposite direction; a rod enclosed in and adjustable endwise of said member having a hair-gripping hook at one end; a nut threaded to one end of said tubular member; and a non-rotatable member movable with said nut and having a recess to receive said single projection.

5. A device of the character described comprising a tubular member provided with a plurality of projections curved in one direction and a single projection curved in the

- opposite direction; a rod enclosed in and adjustable endwise of said member having a hair-gripping hook at one end; a nut threaded to one end of said tubular member; and a nonrotatable member movable with said nut and having a recess to receive said single projection, said nonrotatable member having a slotted hub straddling said single projection. 5
6. A device of the character described comprising a tubular member provided with a plurality of projections curved in one direction and a single projection curved in the opposite direction; a rod enclosed in and adjustable endwise of said member having a hair-gripping hook at one end; a nut threaded to the opposite end of said rod and adapted to coact with an end of said tubular member; and hair-gripping means at the opposite 10 end of said tubular member coacting with said single projection. 15
7. A device of the character described comprising a tubular member provided with a plurality of projections curved in one direction and a single projection curved in the opposite direction; a rod enclosed in and adjustable endwise of said member having a hair-gripping hook at one end adapted to force a lock of hair against an end of said tubular member; and hair-gripping means 20 at the opposite end of said tubular member coacting with said single projection. 25
8. A device of the character described comprising a tubular member provided with a plurality of projections curved in one direction and a single projection curved in the opposite direction; a rod enclosed in and adjustable endwise of said member having a hair-gripping hook at one end; a nut threaded to one end of said tubular member; and a nonrotatable member movable 30 with said nut and having a recess to receive said single projection, said recess having depressions in the opposite walls thereof, depression to receive the hair on said single projection. 40
9. A device of the character described comprising a tubular member provided with a plurality of projections curved in one direction and a single projection curved in the opposite direction; a rod enclosed in and adjustable endwise of said member having a hair-gripping hook at one end; a recess on one end of said tubular member to receive said hook when moved endwise, the inner walls of said recess having oppositely disposed depressions to receive the hair surrounding said hook; and hair-gripping means at the opposite end of said tubular 45 member coacting with said single projection. 50
10. A device of the character described comprising a tubular member provided with a plurality of separated projections extending laterally therefrom; means enclosed in and adjustable endwise of said member for 55
- gripping a lock of hair at one end of said tubular member; and nonrotatable means at the opposite end of said tubular member for gripping said lock of hair at the opposite end of said tubular member. 60
11. A device of the class described comprising a member provided with a plurality of alined projections extending laterally from one side only; and means at opposite ends of said member for gripping a lock of hair wound around said member and alternately around the opposite sides of the projections. 65
12. A device of the class described comprising a member provided with a plurality of alined flat-sided projections extending laterally from one side only; and means at opposite end of said member for gripping a lock of hair wound around said member and alternately around the opposite sides of said projections. 70
13. A device of the class described comprising a member provided with a plurality of alined projections extending laterally from one side only, said projections being larger at the bottom with their outer ends curved in the same direction; and means at opposite ends of said member for gripping a lock of hair wound around said member and alternately around the opposite sides of said projections. 75
14. A device of the class described comprising a member provided with a plurality of alined projections extending laterally from one side only, said projections having their outer ends in alinement and curved in the same direction; and means at opposite ends of said member for gripping a lock of hair wound around said member and alternately around the opposite sides of said projections. 80
15. A device of the class described comprising a cylindrical member having alined curved projections extending laterally from one side only and provided at opposite ends thereof with means whereby a lock of hair wound around said member and alternately around the opposite sides of said projections may be secured. 85
